Term of patent 3½ years

To all whom it may concern:

Be it known that I, Theodore Samuels, a citizen of the United States of America, residing in St. Louis, county of St. Louis, and State of Missouri, have invented a new, original, and ornamental Design for a Shoe, of which the following is a specification, reference being had to the accompanying drawing, forming part thereof,

The essential feature of my design resides in the production of a shoe of the type shown having at the upper portion of the vamp a corset-like band of contrasting color and of substantially uniform width with gussets on either side thereof and a permanent ornamental lacing arrangement on the front of the same.

I claim:

The ornamental design for a shoe, substantially as shown and described.
